METALLIC STRUCTURE AND METHOD OF
MAKING THE SAMEWalter de Fries, Youngstown, Ohio, assignor to
The William B. Pollock Company, Youngs-
town, Ohio, a corporation of Ohio

Application June 23, 1931, Serial No. 546,271

21 Claims. (Cl. 29—164)

The present invention relates broadly to the building or fabrication of metallic structures, and more particularly to structures adapted to be utilized as beams, girders, bodies and the like, although the utility of the invention is not limited with respect to the particular use to which the structures are placed, or the particular cross sectional characteristics or designation thereof.

It has heretofore been customary in many cases to construct so-called box girders or beams from a series of rolled shapes suitably riveted or welded one to the other. Box girders have desirable structural characteristics which are well recognized. In many cases, however, it has heretofore been necessary to utilize I-beams or the like in place of the more desirable box girders for the reason that the cross sectional dimensions of the girders have been such, that it has not been possible for a man to work from the inside thereof as required for the assembly operations and more especially the riveting which has been required.

The present invention has for one of its objects the provision of an improved structure adapted to serve in the capacity of a box girder for example, a beam, or a supporting body. While the invention is useful generally in the building art, it is herein shown more particularly as applied to different features of railway car construction. It is to be understood, however, that the drawings in this respect are illustrative only. In the drawings:

Figure 1 is a top plan view of a portion of a car body constructed in accordance with the present invention;

Figure 2 is a side elevational view of the structure illustrated in Figure 1;

Figure 3 is a transverse sectional view on a line III—III of Figure 1, the section, however, illustrating a complete car body;

Figure 4 is a side elevational view of a portion of a girder constructed in accordance with the present invention and more particularly adapted to be utilized as a side sill for ladle cars and the like;

Figure 5 is a longitudinal sectional view, on an enlarged scale, through a portion of the girder of Figure 4;

Figure 6 is a transverse sectional view, on an enlarged scale, on a line VI—VI of Figure 4;

Figure 7 is a transverse sectional view on an enlarged scale along the line VII—VII of Figure 4, looking in the direction of the arrows;

Figure 8 is a view similar to Figure 1, illus-

trating a different form of car body embodying the present invention;

Figure 9 is a side elevational view of the structure illustrated in Figure 8;

Figure 10 is a detail sectional view on the line X—X of Figure 9, looking in the direction of the arrows;

Figure 11 is a detail sectional view on the line XI—XI of Figure 10, looking in the direction of the arrows; and

Figure 12 is a detail sectional view along the line XII—XII of Figure 10, looking in the direction of the arrows.

With ordinary rolled shapes, the limitations of the rolling operation require the shape to be either of substantially constant cross sectional area throughout the entire length thereof, or of very gradually and uniformly changing cross sectional characteristics. In many cases it is desired to provide a girder, beam, body or the like having a cross section modulus at one point which is materially different from the cross section modulus at a point but slightly removed therefrom. It will be readily apparent that rolled shapes do not lend themselves to such requirements, and it has accordingly been necessary, where rolled shapes have been utilized, to effect more or less of a compromise, providing an average cross section which is heavier than the minimum cross section required at certain points, in order to insure the necessary strength. This has resulted in structures having a materially greater weight than necessary. In the case of buildings, cars and the like, this has meant an unnecessarily large dead load with a consequent reduction in the permissible live load possibilities.

Wherever possible, fabricated girders, such as box girders, have been utilized. In many cases, however, the dimensions of the desired girders have not been such as to permit fabrication in this manner. The present invention is designed to provide a building structure of general utility capable of being effectively fabricated regardless of the cross sectional size, and lending itself to a change in the section modulus as required from point to point in order to afford the necessary strength.

Referring more particularly to Figures 1 to 3 of the drawings, there is illustrated a car body which in many respects is nothing but a modified girder construction. It comprises a top plate or flange 2 and a bottom plate or flange 3 spaced a distance determined by the dimensions desired in the completed car. Extending lon-

itudinally between the plates or flanges are webs 4 which are likewise disposed in spaced relationship. The webs are characterized by the provision at intervals therealong of lugs or 5 projections 5 adapted to interfit with correspondingly shaped openings in the flanges. By reason of this construction, the mere act of assembly of the webs and flanges serves to afford a mechanical interlock therebetween. Prior, however, to the complete assembly of the parts, diaphragm plates 6 are mechanically interlocked both with the webs and flanges. These diaphragm plates are illustrated as comprising substantially rectangular plates having upper and lower projections 7 and side projections 8. The side projections interlock with the webs 4, while the upper and lower projections interlock with the flanges.

The desired interlocked relationship having been obtained during the assembly, the parts may be welded in position. This may be accomplished in a variety of different ways. If desired, the diaphragm plates and webs may be mechanically interlocked and welded as a unit adapted to receive the upper and lower flanges 2 and 3, after which the projections 5 and 7 from the webs and diaphragm plates respectively are welded in position in the flanges. In this manner there is provided a substantially unitary structure composed entirely of plate or plate-like members which are both mechanically interlocked and welded one to the other.

The spacing of the diaphragm plates may be varied in accordance with the load requirements, 35 this being governed by the permissible ratio between the radius of gyration of the weaker members of the structure, and a certain value, usually referred to in engineering as the L/R ratio. This is fixed for structural practice by a value of 120 for members in tension, and between 60 and 90 for members in compression. The diaphragm plates not only give greater stiffness and effect a desirable bracing, but by their number and location enable the strength requirements at different points to be satisfactorily met. This makes possible the use of standard plates for the production of fabricated structures in which the section modulus or radius of gyration varies from point to point.

50 The provision of means for mechanically interlocking the parts is desirable for the reason that the projections transmit by mechanical means a certain portion of the load, thus relieving stresses which would otherwise be imposed entirely on welded joints. This makes possible the use of lighter welds and obviates the difficulties which have heretofore been experienced in the case of welds which were not properly effected.

60 In the embodiment illustrated in the figures of the drawings just referred to, the top flange 2 is of materially greater width than the bottom flange, so as to overhang the edge portions thereof. The overhanging portion of the top flange may be reinforced by gussets 9 having projections 10 for interlocking engagement with the webs 4 and other projections 11 for interlocking engagement with the edge portions of the upper flange 2.

70 It will be apparent to those skilled in the art that the utilization of plate or plate-like members for the construction of a car body enables a car body of the desired strength to be comparatively inexpensively constructed which will have 75 a minimum weight, thereby correspondingly in-

creasing the load carrying capacity of the car.

In Figures 4 to 7 of the drawings there is illustrated a slightly modified embodiment of the invention. In these figures there is shown the end portion of a car sill or girder comprising a top flange 12, a bottom flange 14, and inner and outer webs 15 and 16 respectively. In this embodiment, the flanges and webs are shown as being of different thicknesses, the flanges being materially heavier than the webs. Extending between the flanges are diaphragm plates 17 of such length that the end portions thereof will extend through suitably shaped openings in the webs 15 and 16 so as to be mechanically interlocked therewith.

During the assembly of a structural member of the type illustrated in these figures of the drawings, the diaphragm plates will be first welded in position between the flanges as indicated by the reference character 18. Thereafter, the webs will be applied so as to interlock with the projecting ends of the diaphragm plates 17, and the webs and flanges welded one to the other as indicated at 19. Thereafter the projecting ends of the diaphragm plates may likewise be welded in position to the webs. Such a construction provides a box girder or beam which may be effectively utilized for any desired purpose. By providing the diaphragm plates with openings 20, provision is made for the running of conduits, cables, pipes or the like longitudinally of the beam structure. By previously individually shaping the webs and flanges, the completed structure may have a contour such that it is adapted for use in the desired structural relationship to other parts.

In Figures 8 to 12 of the drawings there is shown a portion of a car frame in which all of the parts are composed either of structural or plate members and in which all of the parts are mechanically interlocked and welded, thus forming what may be termed, for all practical purposes, a one-piece structure. From Figure 8 it will be apparent that the car structure comprises side sills 22, which are of identical construction, and which cooperate through the medium of welded and interlocked joints, herein-after described, with an end frame 23. In Figure 8 there is only shown one end of a car, it being apparent that the two ends are of similar construction. Each side sill comprises a top flange 24 and a bottom flange 25 between which are welded webs 26. These webs are formed with projections 27 which project through openings in the flanges and are welded thereto.

Where it is desired to provide a greater section modulus, recourse may be had to the provision of filler flanges 28 as shown in Figure 10, these filler flanges being welded both to the main flanges and to the webs. This provides in effect a laminated flange structure. In like manner the webs themselves may be reinforced throughout portions of their lengths. Where filler flanges are utilized, they are welded in position between the webs before their main flanges are assembled thereon, the entire structure being subsequently welded at the desired points. There is thus formed a beam or girder comprising mechanically interlocked webs and flanges, as in the structures already described.

70
75

Where the beams or girders are utilized as sills and comprise different portions angularly disposed, the projections 27 will conveniently be formed as indicated more particularly in Figure 9 with the end walls of the projections so in-

clined that the flanges may be applied by a true lateral movement. In other words, the ends of all of the projections will preferably be parallel.

5 Extending transversely between the side sills 22 is a bar 29 which passes through suitable slots both in the inner and outer webs, the ends of the bar lying flush with the outer web of the sills. The outer web is preferably formed 10 from a plate of suitable dimensions to provide adjacent each end thereof a bracket 30 and a beam engaging portion 31. The inner web of each sill terminates short of the outer web and is adapted to abut at its end against the web of 15 a beam 32. This beam is of such length as to fit into a correspondingly shaped slot in the beam portion 31 so as to permit welding of the same therein. Projecting upwardly from the bar 29, as illustrated more particularly in Figure 11 of the drawings, is a trunnion supporting plate 33 welded at its lower edge to the bar 29 as indicated at 34. Secured to its upper end is a horizontally extending plate 35 welded at one edge to the plate 33 and at its opposite edge 20 to the upstanding portion 36 of a deck plate 37, thus forming a girder with two flanges and a single web similar to a rolled I or H beam shape.

Extending between the trunnion supporting plate 33, the plate 35, the deck plate 37, the 30 beam 32 and the bar 29, is a series of ribs 38. Each of these ribs is provided with a projection 39 adapted to mechanically interlock with a correspondingly shaped slot in the trunnion supporting plate 33 and with a second projection 35 40 adapted to mechanically interlock with the deck plate 37. The trunnion supporting plate is further braced by means of gussets 41 welded in position between the same and the bar 29. By reference more particularly to Figure 9 of the drawings, it will be apparent that the trunnion supporting plate 33 is likewise formed with end projections 42 which extend through suitably shaped openings in the bracket portion 30 of the outer web 26 so as to mechanically interlock these parts.

Secured in position between the trunnion supporting plate 33 and the upstanding portion 36 of the deck plate are bearing members 43, conveniently formed of cast iron. These bearings, as will be apparent more particularly from Figure 12 of the drawings, are formed with shoulders 44 adapted to overlie the upper edges of the respective plates so as to be held against downward movement relatively thereto. The 50 plates and bearings are further held in position by through bolts or rivets 45. The bearings at their upper ends are shaped to provide trunnion supports 46 for cooperation with the end trunnions usually provided on ladies and the like.

Intermediate the bearings 43 the upstanding portion 36 of the deck plate 37 is provided with an inturned flange 46 for stiffening purposes. The ends of the flange 46 bear against the adjacent ends of the bearings 43, and the inwardly facing channel formed between the flange 46 and the plate 35 may be reinforced by any suitable number and arrangement of stiffening ribs 47 welded in position therein.

70 Suitably secured to the beam 32 is a draft gear housing 48, this draft gear housing lying under the deck plate 37 and preferably mechanically interlocked therewith through the medium of projections 49. While the draft gear housing may be of any preferred construction, it is

conveniently also formed of plate members, as illustrated. The end frame is completed by side plates 50 which are suitably welded in position to the deck plate at the upper edge, and to the beam portions 31 of the webs 26 at their ends as indicated at 51.

From the foregoing description, it will be apparent that the sills formed entirely of plate members which are themselves interlocked and welded, are interlocked and welded both to a 10 bar 29 which extends through the web plates of the sill and to a beam 32 which is mechanically interlocked with the outer web plates of the sills through the medium of the beam portions 31 thereof, and against which the inner 15 ends of the webs 26 abut in such manner that they may likewise be welded to the beam.

With the exception of the bearings 43 which are conveniently of cast iron by reason of the strength and inexpensiveness of such material, 20 the entire end frame is composed of plate members and structural members, all of which members are mechanically interlocked and welded. This provides a one-piece frame, for all practical purposes, and one giving a maximum of 25 strength with a minimum weight. Any portion of the entire frame may be reinforced or strengthened by the provision of suitable ribs, or by the provision of stiffening laminations welded thereto over any portion thereof. The 30 beam 32 is illustrative of one type of reinforcing, such reinforcing comprising ribs 53 welded in position between the flanges and web of the beam.

As before stated, the drawings selected for 35 purposes of illustrating the present invention are particularly directed to structures adapted for use in the construction of cars or car bodies. They are representative, however, of built up structures which may be utilized for any 40 desired building purposes wherein strength combined with lightness is a desirable factor.

Attention has already been called to the fact that in accordance with the present invention, it is possible to pre-shape the individual parts 45 utilized for the construction of a finished article. This constitutes an important advantage, in that it eliminates the difficulties attendant upon the proper shaping of previously formed articles or bodies. Thus, for example, 50 in the case of rolled beams, any after shaping operation tends, by reason of elongation, to thin down certain of the parts, and by compression, to thicken other of the parts. By pre-shaping the component parts, and afterwards 55 assembling the same, the desired cross sectional characteristics may be maintained throughout the entire length of the article.

In the illustrated embodiments of the invention, I have shown structures in which the webs, 60 where two or more are utilized, are in substantially parallel relationship. This is also true as to the flanges. It is apparent, however, that such a parallel relationship is not essential, the same advantages of construction being obtainable where either the webs or the flanges or both are in angular relationship one to the other.

It will be understood that while I have herein 70 illustrated and described certain preferred embodiments of my invention, the drawings are illustrative only, and typify various shapes and structures embodying the invention and in which changes can be made without departing either from the spirit of the invention or the scope of 75

my broader claims. To this end the term "girder" is hereinafter utilized in the claims as signifying a body, beam, sill or the like having the characteristics ascribed thereto, the term being 5 one of definition and not one of limitation.

I claim:

1. In the method of forming a structural shape such as a box girder, the steps comprising separately preforming web and flange members, securing lugged diaphragm plates to certain of said members transversely between the same, mechanically interlocking the remaining members in position by the lugs of said plates to form a structure closed on four sides, and welding 10 the structure including welding along outside joints thereof and welding from without the structure said lugs in position.
2. In the method of forming a box girder, the steps comprising separately preforming web 20 and flange members, securing diaphragm plates transversely between longitudinally disposed web members, mechanically interlocking the flange members with said diaphragm plates and with said web members to form a structure closed 25 on four sides, and welding the mechanically interlocked flange members in position including welding along outside joints of the closed structure.
3. In the method of forming a structural 30 shape, the steps comprising separately preforming web and flange members to provide one with parallel lugs and the other with openings to receive said lugs, securing transverse diaphragm plates to the lugged members, assembling the 35 other members with the lugged members so that the lugs are received in said openings, the assembled web and flange members constituting a structural shape closed on four sides, and welding the assembled structural shape including welding along outside joints thereof and 40 welding the lugs in position.
4. In the method of forming a structural shape, the steps comprising separately preforming web and flange members to provide one 45 with parallel lugs and the other with lug receiving openings, securing lugged diaphragm plates to the lugged members transversely between the same, assembling the other members with the lugged members so that the lugs of 50 the plates and lugged members are received in said openings, the assembled web and flange members constituting a structural shape closed on four sides, and welding the assembled structural shape including welding along outside 55 joints thereof and welding certain of said lugs in position.
5. In the method of fabricating a box girder, the steps comprising separately preshaping web 60 and flange members, securing lugged diaphragm plates transversely between the flange members, mechanically interlocking the web members with the diaphragm plates by means of said lugs, and welding along the outside of joints between members.
6. As an article of manufacture, a box girder 65 comprising longitudinal flanges, longitudinal webs disposed edgewise between the flanges, and transverse diaphragm plates mechanically interlocked with both the webs and the flanges by lugs extending into the webs and the flanges, certain of said webs and flanges being welded along outside joints therebetween.
7. As an article of manufacture, a box girder 70 comprising a pair of longitudinally extending webs, a pair of longitudinally extending flanges

cooperating with the opposite edges of said webs to provide a structure closed on four sides, said webs and flanges being mechanically interlocked by lugs on one received in recesses in the other, and diaphragm plates having integral lugs projecting in the direction of said first-mentioned lugs, said diaphragm plates being fixed in transverse position within said box girder by said integral lugs, said webs and flanges being welded along outside joints.

8. As an article of manufacture, a box girder comprising a pair of flanges in substantially parallel relationship, a pair of webs in similar relationship but edgewise disposed with respect to said flanges, said webs and flanges being welded together along outside joints and forming a structure closed on four sides, and diaphragm plates positioned transversely within said girder by lugs integral therewith, said diaphragm plates bearing against the opposed faces 20 of the flanges to stiffen the girder.

9. As an article of manufacture, a box girder comprising a pair of curved flange members spaced by transverse diaphragm plates, and web members mechanically interlocked with said diaphragm plates and welded along the outside 25 of the joints with the flange members, the girder structure formed by the web and flange members being closed on four sides.

10. As an article of manufacture, a structural 30 shape comprising an upper compression plate and a lower tension plate constituting flanges, a series of longitudinal webs disposed edgewise between the plates, the webs having parallelly extending lugs and the plates having corresponding openings for receiving the lugs to mechanically interlock the webs and plates, and diaphragm plates transversely disposed between adjacent webs and acting as struts between the flanges, the outermost webs of the series being 40 welded to said compression and tension plates.

11. As an article of manufacture, a box girder comprising flanges, webs cooperating with the flanges to provide a structure closed on four sides, certain of said webs being welded to said flanges, and transverse diaphragm plates mechanically interlocking the webs and flanges, the diaphragm plates each having projecting portions received in respective openings in a web and flange and subject therein to shearing 50 stresses.

12. As an article of manufacture, a car body comprising a lower tension and an upper compression member, webs disposed edgewise intermediate the tension and compression members 55 and welded thereto along outside joints, and means for mechanically interlocking said members and webs, said members and webs being of flat rolled stock.

13. As an article of manufacture, a truss in 60 the form of a box girder comprising upper and lower flanges acting as main compression and tension members of the truss, webs welded to the flanges, and transversely disposed diaphragm plates mechanically interlocking said webs and flanges by having projecting portions received in corresponding openings of the webs and flanges for transmitting shearing stresses between the members of the truss, the diaphragm plates being enclosed on four sides and bearing 65 at the top and bottom against the flanges and at both sides against webs.

14. As an article of manufacture, a truss in 70 the form of a box girder comprising primary tension and compression flanges, diaphragm 75

plates acting as secondary compression members or struts for holding said flanges in spaced relationship, said diaphragms having at their free edges integral shear keys, and plates welded 5 to said flanges as webs or secondary tension members, said web plates being formed with openings receiving said shear keys and said shear keys being welded therein, the entire assembly being fabricated from flat rolled stock.

10 15. In the method of manufacturing a box girder having a bowed portion, the steps comprising separately preforming correspondingly bowed web and flange members, providing one with parallel lugs and the other with openings 15 to receive said lugs, securing transverse diaphragm plates to the lugged members, assembling the other members with the lugged members so that the lugs are received in said openings, and welding the assembled girder including welding 20 along outside joints thereof.

16. As an article of manufacture, a car body comprising longitudinal flanges, a plurality of longitudinal webs disposed edgewise between the longitudinal flanges, and transverse diaphragm 25 plates mechanically interlocked with both the webs and flanges by lugs extending into the webs and the flanges, the outside joints between the flanges and certain of said webs being welded.

17. As an article of manufacture, a car body 30 comprising end frames and box girders constituting car sills, each box girder comprising a pair of curved flange members spaced by transverse diaphragm plates and web members mechanically interlocked with said diaphragm 35 plates and welded along the outside of the joints with the flange members, the girder structures formed by the web and flange members being each closed on four sides and the ends thereof being extended and interlocked with the end frames.

18. As an article of manufacture, a box girder

comprising a series of longitudinally extending webs, a pair of opposed longitudinally extending flanges cooperating with opposite edges of said webs, and diaphragm plates transversely disposed between webs and mechanically interlocked with both the webs and the flanges by lugs extending into the webs and the flanges, certain of said webs and flanges being welded along outside joints therebetween.

19. In a car structure, box girders constituting car sills, said box girders comprising inner and outer webs and upper and lower flanges welded along outside joints therebetween, and an end frame including a transverse beam, the outer webs of the box girders being extended beyond 15 said transverse beam and having openings receiving the ends thereof.

20. In a car structure, box girders constituting car sills, each of said box girders comprising web members, flange members, said web members and flange members being welded along outside joints, and transverse diaphragm plates having projecting lugs interlocking said plates with certain of said members, and an end frame including a transverse beam interlocked with the 25 car sills by having the ends of the beam entered in an opening in a web member of each.

21. In a car structure, an end frame including a transverse load carrying structural member, trunnion bearings carried thereby, and box 30 girders constituting car sills, each of said box girders comprising inner and outer webs and upper and lower flanges welded together along outside joints and mechanically interlocked by transverse diaphragm plates with projecting lugs, 35 said transverse structural member being interlocked with the sills by having its ends entered in an opening in the outer web and abutting the end of the inner web of each sill.

40
WALTER DE FRIES.
